UNITED STATES PATENT OFFICE.

CHARLES H. NORTON, OF NEW YORK, N. Y.

FIREMAN'S HELMET.

1,206,356.

Specification of Letters Patent. Patented Nov. 28, 1916.

Application filed March 20, 1916. Serial No. 85,481.

To all whom it may concern:

Be it known that I, CHARLES H. NORTON, a citizen of the United States, residing at New York, in the county of New York, State of New York, have invented certain new and useful improvements in Firemen's Helmets; and I do hereby declare the following to be a full, clear, and exact description of the invention, such as will enable others skilled in the art to which it appertains to make and use the same.

This invention relates to fireman's hats or helmets, and aims primarily to provide improved means whereby the wearer of the helmet may signal to others at a distance.

A further object of the invention is to provide means in connection with a hat or helmet whereby the wearer may give various signs or signals, and whereby when not in use as a signaling device the light of the helmet will be unimpaired to afford means for lighting the way for the wearer.

A still further object of the invention is to provide a device of the character described which is of simple and inexpensive construction, which is composed of but few readily assembled parts, all so arranged as to preclude breakage or derangement of the same, which may be easily and quickly actuated, and which will prove thoroughly efficient in the attainment of the ends for which it is designed.

With these objects in view, together with others which will appear as the description proceeds, the invention resides in the novel combination and arrangement of parts, all as will be described more fully hereinafter, illustrated in the drawings and particularly pointed out in the claims.

The invention will be best understood by reference to the accompanying drawings, wherein:

Figure 1, is a vertical sectional view taken through a conventional form of fire helmet, and illustrating the application of a signaling mechanism embodying my invention, Fig. 2, is a sectional view taken on line 2—2 of Fig. 1, and illustrating the signaling panes moved to inoperative position, Fig. 3, is a view similar to Fig. 2 and illustrating one of the signaling panes moved into alignment with the lamp, and Fig. 4, is a horizontal sectional view taken on line 4—4 of Fig. 1 and showing the signaling panes retracted.

Referring now more particularly to the

drawings 5 indicates a fireman's helmet, within the upper portion of which is arranged a reflector 6, covered or inclosed at its forward end by a diaphanous pane 7. 60 Projecting into the reflector 7 at the rear portion thereof is a lamp in the form of an ordinary electric light bulb 8, which derives its electrical energy through the wires 9 from a battery 10 supported within the 65 hat and behind the said reflector. A switch 11 may be included in the wiring circuit to have its operating handle or knob project beyond the exterior of the hat in a place for convenient manipulation by the hand of the 70 hat or helmet wearer. It is apparent from this construction that the lamp 8 may be ignited to project light rays through the reflector upon manipulation of the switch 11, and when not needed the light may be 75 readily extinguished.

The signaling mechanism employed in connection with the above described lighting system comprises a pair of diaphanous panes 12 and 13 respectively; the said panes 80 being adapted when not in use to be retracted from the reflector, but when desired may be selectively operated or moved to lie in alignment with the rays projected from the lamp 8. These panes are preferably of 85 different colors, so that colored lights may be projected from the hat upon manipulation of the panes. For conveniently operating these panes, a shaft 14 is mounted for rotation within the helmet beneath the reflector 6, and projects forwardly from the hat to provide an operating knob or handle 15. The panes 12 and 13 may be inclosed by suitable rims 16, to each of which is connected arms 17 and 18 respectively, the opposite extremities of the arms being rotatably mounted upon the shaft 14. Shoulders 19 are arranged on each of the arms 17 and 18, which shoulders are adapted to be engaged by a stud or pin 20 carried by 160 the shaft 14. Upon rotation of the shaft in one direction, the stud 20 will engage with the shoulder 19 on one of the pane arms to move the same inwardly of the reflector to lie in such position as to place the pane 105 carried thereby in direct alignment with the lamp 8, whereupon the rays of the latter will be projected therethrough to give a light the color of the adjacent signal pane. Upon rotation of the shaft in a reverse direction the arm will be permitted to gravitate to withdraw or retract the pane out of 110

alinement with the light rays, and further reverse movement of the shaft will operate through the stud 20 to move the opposing pane into alinement with the light rays, whereupon a light will be projected through the latter colored pane. Upon movement of the shaft to such position that the stud 20 will be disposed downwardly, both panes 12 and 13 will be retracted, whereupon the hot light may be utilized as a search light, the colored panes not interfering with the use of the light in this latter respect.

The opposite sides of the reflector 6 are slotted as at 21, through which slots the said panes 12 and 13 respectively may drop when not in use. From this construction it is apparent that a simple and extremely efficient signaling device is provided, and one wherein variously colored lights may be shown to apprise the companions of the wearer of his dangerous position, of his need of help, or the signals may be utilized to direct others of the course to pursue in the work undertaken.

25 While I have herein shown and described a particular or preferred embodiment of the invention, I wish it to be understood that I need not confine myself to all the precise details of construction herein set forth 30 by way of illustration, as modification and variation may be made without departing

from the spirit of the invention or exceeding the scope of the claims.

What is claimed is:

1. In a device of the class described, the combination with a helmet having a lamp and a reflector therefor, of a shaft in said helmet, arms carried by said shaft and projecting divergently into said reflector, panes on the ends of said arms, the said reflector 40 being provided with slots for the reception of said panes, and means on said shaft and arms for selectively projecting said panes into the path of light emanating from said lamp, substantially as described. 45

2. In a device of the class described, the combination with a reflector provided with oppositely disposed slots, of a shaft mounted for rotation beneath said reflector, a stud on said shaft, arms rotatably mounted on said shaft and projecting into said reflector, panes on the ends of said arms adapted to slide within said slots to the exterior of said reflector, and shoulders on said arms adapted to be engaged by said stud, substantially as described. 50 55

In testimony whereof, I affix my signature, in the presence of two witnesses.

CHARLES H. NORTON.
